United States Patent Office.

BENTLEY C. BIBB, OF BALTIMORE, MARYLAND.

Letters Patent No. 97,027, dated November 23, 1869.

IMPROVEMENT IN FIRE-PLACE STOVES.

The Schedule referred to in these Letters Patent and making part of the same

To all whom it may concern:

Be it known that I, BENTLEY C. BIBB, of the city of Baltimore, and State of Maryland, have invented a new and improved Fender for Fire-Place Stoves; and I do hereby declare that the following is a full, clear, and exact description thereof, reference being had to the accompanying drawings, making part of this specification, in which—

Figure 1 is a perspective view of the improved fender.

Figure 2 is a perspective view of the same, applied to a fire-place stove, showing the movable segment turned up to allow the withdrawal of the ash-pan.

Figure 3 is a top view.

Figure 4 is a front elevation.

Figure 5 is a vertical central transverse section.

Similar letters of reference indicate corresponding parts in the several figures.

The object of this invention is to pivot the central section of a fender-rail to two lateral sections of the rail, in such manner that while the fender is in place in front of the base of a fire-place stove, the movable portion of the rail can be turned up, so as to allow of the withdrawal of the ash-pan from the stove, as will be hereinafter explained.

The following description of my invention will enable others skilled in the art to carry it into effect.

In the accompanying drawings—

A represents the base of the fender, which is of the shape of a segment of a circle externally, and curved internally, so as to fit snugly against the front wall of the stove-base D, as shown in fig. 2.

From the base A rise perpendicularly four posts, *a a*, which support two segments, B B, of the fender-guard or rail.

These sections, B B, are thus rigidly and permanently attached to their base.

Between the inner ends of sections B B, a space is left sufficient to allow an ash-pan, E, to be drawn through it, as in the act of removing or replacing such pan.

C is the third or movable section of the rail, which is made movable by pivoting it to the ends of the fixed sections, as at O C, so that it can be turned up from a horizontal position, as shown in figs. 2 and 5; and, in consequence of its curved form, it will, when in this position, resting against the base of the stove, form an arch, beneath which the ash-pan E can be moved out of or into its place.

When the rail-section C is in the position shown in figs. 1, 3, 4, that is to say, when it is in the horizontal plane of sections B B, it may be supported by the bifurcated props *b b*, resting against the inner posts *a a*, or by lugs cast on this section C, abutting against corresponding lugs or stops on the rail-sections B B, or inside posts *a a*, or, if deemed best, one of the posts of the fender may be attached to the pivoted section, and thus, when this section is thrown down, it will be supported by said posts.

By my invention the good appearance of a fender-rail is in nowise injured, while a portion of it can be conveniently turned up out of the way of the ash-drawer, to allow the removal or replacement thereof; and while this is the case, it will not be necessary to remove the entire fender for effecting said object.

Having described my invention,

What I claim as new, is—

A vertically-movable pivoted or swinging fender-rail section, C, substantially as and for the purposes described.

BENTLEY C. BIBB.
